UNITED STATES PATENT OFFICE.

CHARLES A. SWACKHAMMER, OF COTTAM, ONTARIO, CANADA.

ROTARY VALVE.

1,140,206.

Specification of Letters Patent.

Patented May 18, 1915.

Application filed August 11, 1914. Serial No. 856,267.

To all whom it may concern:

Be it known that I, CHARLES A. SWACKHAMMER, a subject of the King of Great Britain, residing at Cottam, in the Province

5 of Ontario and Dominion of Canada, have invented certain new and useful Improvements in Rotary Valves; and I do hereby declare the following to be a full, clear, and exact description of the invention, such as

10 will enable others skilled in the art to which it appertains to make and use the same.

My invention relates to new and useful improvements in valves, particularly for gas engines and has for its object to generally 15 improve rotary valves so that warping thereof is prevented and leakage of gas is effectually prevented or reduced to a minimum.

Another important object of my invention 20 is to provide a valve of the character described which owing to its peculiar construction insures the proper opening and closing of the ports and reliable operation of the engine to which it is attached.

25 Another important object of my invention is to provide a valve of the character described which is extremely simple as to construction, reliable and efficient in operation and cheap to manufacture.

30 The above and additional objects are accomplished by such means as are illustrated in the accompanying drawings, described in the following specification and then more particularly pointed out as claimed.

35 With reference to the drawings, wherein I have illustrated the preferred embodiment of my invention as it is reduced to practice, and throughout the several views of which similar reference numerals designate

40 corresponding parts: Figure 1 is a vertical fragmentary sectional view of an engine cylinder showing my improved valve in operative position and a portion of the operating mechanism therefor, Fig. 2 is a 45 top plan view, Fig. 3 is a detail perspective of my improved valve removed from the cylinder, and Fig. 4 is a top plan view of a modified form of valve wherein the ports are elongated instead of circular.

50 Referring to the drawings by characters of reference, the numeral 1 designates as an entirely an engine cylinder having the usual upper wall or head 2 through which is formed intake and exhaust ports 3 and 4 respectively. The outer face of the wall or

head 2 of the cylinder 1 is provided with a shallow circular recess 5 to rotatably receive my improved valve to be later described.

As a means for holding my improved 60 valve in operative position upon the recess 5 I provide a plate 6 secured upon the wall or head 2 by bolts 7 and removable therefrom. The plate 6 is provided with openings 8 and 9 which communicate respectively with the ports 3 and 4 and are suitably connected after a manner not shown with the intake and exhaust pipes. The inner face of the plate 6 bears upon the outer face of the valve and serves to hold the valve 70 in place and it being removable enables the ready assembling and disassembling of the valve.

My improved valve comprises a circular disk 10 that is provided with a plurality of 75 arcuately arranged and spaced openings 11 that are arranged to coöperate with the ports 3 and 4 and openings 8 and 9 after a manner which will be later more fully described. A depending peripheral flange 12 80 is formed on the disk 10 and is positioned within a circular groove 13 formed in the upper face of the head or top wall 2 of the cylinder 1. This groove 13 opens into the recess 5 around the side wall of said recess. 85 A depending circular flange 14 is formed on the disk 10, is spaced circumferentially from the flange 12 and positioned within a groove 15 similar to the one 13 that is formed in the head or top wall 2 of the cylinder 1. 90 The flanges 12 and 14 are arranged to rotate within the grooves 13 and 15 and serve to insure the proper registration of the openings 11 in the valve with the intake and exhaust ports. 95

The forming of the flanges 12 and 14 and peculiar disposition thereof not only serves as a guide in insuring the proper operation of the valve but materially strengthens the valve in such a way that warping thereof 100 is prevented or reduced to a minimum since they act as reinforcing elements. A vertical offstanding pin 16 is carried centrally of the disk 10 and extends through a central aperture in the plate 6. Keyed upon the upper end of the pin 16 is a bevel gear 17 that coöperates with a similar gear 18 keyed upon one end of a shaft 19 that is operatively connected with some rotating part of the engine after a manner not 110

shown. Through the medium of the gears 17 and 18 and coöperating parts, the valve is rotated.

The openings 8 and 9 and corresponding ports 3 and 4 are arranged diametrically opposite while the openings 11 in the valve are arranged in such a way that no one of them is opposite another thus the proper intaking and exhausting action is proved. I 10 preferably provide five openings in the valve so that it may be readily adapted for use in connection with two and four cycle engines.

It will be noted that the openings 11 in the valve or disk 10 are positioned between the 15 flanges 12 and 14 thus no interference of proper registration of the openings 11 with the ports is had by the flanges.

The positioning of the disk within the recess 5 and the provision of the peculiarly 20 arranged flanges 12 and 14 on the disk that rotate within grooves 13 and 15 in combination with the clamping action provided by the plate 6 prevents leaking of the valve, warping, eliminates friction and insures the 25 proper operation of the valve.

In practice, I have found that the form of my invention, illustrated in the drawings and referred to in the above description, as the preferred embodiment, is the most efficient and practical; yet realizing that the 30 conditions concurrent with the adoption of my device will necessarily vary, I desire to emphasize the fact that various minor changes in details of construction, proportion and arrangement of parts may be resorted to, when required, without sacrificing any of 35 the advantages of my invention, as set forth.

What is claimed is:—

1. The combination with an engine cylinder of a disk having a plurality of spaced

apertures therein, the upper wall of said cylinder being provided with a recess to rotatably receive said disk, said cylinder having opposed intake and exhaust ports in its upper wall, a plate removably secured to 45 said cylinder and engaging said disk, said plate having openings therein alining with the intake and exhaust ports, means for rotating said disk and spaced circumferential flanges formed on said disk and rotatably mounted in grooves in the upper wall of said cylinder.

2. The combination with an engine cylinder having its upper wall provided upon its outer face with a circular recess and circular grooves in said upper wall communicating with said recess and spaced from each other of a circular disk rotatably mounted within said recess and provided with a plurality of spaced openings, intake and exhaust ports formed in the upper wall of said cylinder and adapted to communicate with the openings in said disk, and plates having openings therein alining with the intake and exhaust ports secured upon the upper wall of said cylinder and engaging the outer face of said disk, a pin rigid with the central portion of said disk and extending upwardly through said plate, means for rotating said disk and operatively connected with said pin and spaced circumferential flanges formed upon one side of said disk and rotatably mounted within said grooves.

In testimony whereof I affix my signature 75 in presence of two witnesses.

CHARLES A. SWACKHAMMER.
